US00D765098S

(12) United States Design Patent (10) Patent No.: US D765,098 S
Chaudhri et al. (45) Date of Patent: * Aug. 30, 2016

(54) DISPLAY SCREEN OR PORTION THEREOF
WITH GRAPHICAL USER INTERFACE

(71) Applicant: Apple Inc., Cupertino, CA (US)

(72) Inventors: Imran Chaudhri, San Francisco, CA (US); Kevin Will Chen, Sunnyvale, CA (US); Alan C. Dye, San Francisco, CA (US); Dylan Ross Edwards, San Jose, CA (US); Christopher Foss, San Francisco, CA (US); David C. Graham, Campbell, CA (US); Aurelio Guzmán, San Jose, CA (US); Jonathan P. Ive, San Francisco, CA (US); Chanaka Karunamuni, Cupertino, CA (US); Wan Si Wan, Sunnyvale, CA (US); Christopher Wilson, San Francisco, CA (US); Eric Lance Wilson, San Jose, CA (US)

(73) Assignee: Apple Inc., Cupertino, CA (US)

() Term: 14 Years

(21) Appl. No.: 29/519,744

(22) Filed: Mar. 6, 2015

(51) LOC (10) Cl. 14-04
(52) U.S. Cl. USPC D14/485

(58) Field of Classification Search
USPC D14/485-495
CPC G06F 3/0481; G06F 3/04817; H04N 1/00424

See application file for complete search history.

(57) CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.

1 Claim, 2 Drawing Sheets
(2 of 2 Drawing Sheet(s) Filed in Color)
